FIELD COIL CONSTRUCTION

Ralph E. Ferris and Maurice F. Jones, Pittsburgh,
Pa., assignors to Westinghouse Electric Corporation,
East Pittsburgh, Pa., a corporation of
Pennsylvania

Application August 19, 1948, Serial No. 45,128

4 Claims. (Cl. 171—252)

1

Our invention relates generically to electric machines, but it was designed for, and has more particular relation to, the main-field winding of a series commutator dynamo-electric machine of a type which is provided with interpole windings as well as main-field windings. Still more particularly, our invention relates to single-phase series commutator-motors such as are used for traction-purposes in electric-railway practice.

The stator-windings for single-phase series commutator motors have always been difficult and very expensive to make and assemble, on account of the slot-arrangements which are necessitated by the electrical design.

Our invention is an improvement over the subject-matter of a copending application of Carl H. Sutherland, Serial No. 39,321, filed July 17, 1948, which covers a novel type of slot-arrangement, and a novel type of split main-field coil which was considered necessary in order to make the coil-assembly.

It is an object of our present invention to provide a main-field coil which is composed of a plurality of thin (and therefore flexible) copper conductors which are connected either in series, parallel, or series-parallel as may be dictated by the voltage-requirements. It is a characteristic feature of our invention that each main-field coil is pre-formed and completely insulated before being placed in the stator-slots of the motor; and the coil-sides, or portions of the coil which are to lie in the slots, are given the usual impregnation-treatment and hardening-treatment which is necessary to withstand the voltage-strain from the conductors to the core-laminations; while the end-portions of the coil, as pre-formed, are not given any impregnating and/or heating treatment which would harden them, so that these end-portions of the coil remain flexible, due to the stranded construction, thus permitting the coil to be spread temporarily for the purpose of passing over the main-pole tips in the process of assembly, after which said end-portions may be given any necessary additional insulating treatment.

With the foregoing and other objects in view, our invention consists in the combinations, systems, methods, machines and parts, hereinafter described and claimed, and illustrated in the accompanying drawing, wherein:

Figure 1 is a conventional diagrammatic view of a series interpole single-phase commutator-motor of the type to which our invention applies;

Fig. 2 is a fragmentary transverse-sectional view of a portion of the stator-member, showing, in full lines, a sectional view of a main-field coil

2

in its final position, and also a guiding-block or tool which is useful in getting said coil into position, and showing, in dotted lines, two intermediate positions of the same coil; and

5 Fig. 3 is a plan-view diagram of a preformed main-field coil, with a dotted-line indication of the spread condition which it assumed in the process of getting it into position in the motor.

By way of concrete illustration, our invention 10 is shown, in Fig. 1, as being applied to a type of single-phase commutator-motor having a stationary member including a main-field winding 5 and an interpole-winding 6, said motor also having a rotatable commutator-type armature-winding 7, 15 which is schematically or diagrammatically indicated by means of a single circle 7, which represents both the armature-core, the armature-winding, and the commutator which is associated therewith. The field-member 5—6 and the rotor-member 7 are separated by an airgap 8. Brushes 9 bear on the commutator. The motor in Fig. 1 is supplied with electrical power from a single-phase line L1—L2, which serially includes the interpole-winding 6, the main-field winding 5, and 25 the armature 7.

As shown in Fig. 2 of the accompanying drawing, and as described and claimed more particularly in the Sutherland application, the stationary field-member, which carries the field-winding 5 and the interpole-winding 6, also includes a stator-core 11 which is made up of a stack of stator-punchings, the airgap-periphery of which is provided with slots 12, between which are the stator "teeth." The stator "teeth" are of two kinds, alternating between small, straight-sided teeth which constitute the interpoles 13, and larger teeth which constitute the main poles 14 and which have pole-tips 14' in the pole-face portions at the airgap 8.

40 The pole-arrangement just described makes the slots 12 have a special shape, with the slots disposed in "back-to-back" pairs of slots, with the so-called "backs" of each pair of slots in the form of straight, open, slot-portions 15 which are disposed on opposite sides of an intervening interpole 13 of the stator-core 11. These open slot-portions are open to the gap 8, or to the periphery of the core which faces the rotating armature-member 7 of the motor. Each of the slots 12 also 45 has an enlarged "front" portion 16, by which we mean a portion which extends away from the intervening interpole 13 which is disposed between the two slots of a given pair of "back-to-back" slots. These "front" slot-portions 16 have no 50 slot-opening other than the slot-opening 17 of the

open-slotted "backs" of the same slot. This enlarged "front" portion 16 of each slot thus borders, or constitutes one side of, one of the main-field poles 14 and one of its pole-tips 14'.

The main-field winding 5 of Fig. 1 consists of as many main-field coils 5' as there are motor-poles, each coil 5' encircling one of the main poles 14 of the field-core 11, and there are more than two main poles. In like manner, the interpole winding 6 of Fig. 1 consists of a like number of interpole-coils, each encircling one of the interpoles 13. The two sides of any interpole 13 are parallel to each other, so that no problem is involved in getting the various coils of the interpole-winding 6 into place, once the main-field coils 5' have been assembled on the field-core 11.

In accordance with our invention, the main-field coils 5' are pre-formed of a stranded construction, composed of a plurality of thin copper straps or square wires 20, as shown in Fig. 2 and in the broken-away portion of Fig. 3. These stranded conductors 20 are completely insulated and wrapped or taped, before being placed in the stator-slots 12 of the motor. The coil-sides, or straight side-portions between the lines 21 and 22 of Fig. 3, lie in the slots, and are given the usual impregnation-treatment and hardening-treatment which is commonly given to pre-formed coils to make them withstand the voltage-strain from the conductors 20 to the core-laminations 11 bordering the slot-fronts" 16. In accordance with our invention, however, the end-portions 23 of our main-field coils 5' are not given any impregnating and/or heating treatment which would harden these end-portions in the pre-formed condition of the coils 5', before they are placed in the stator-slots 12.

In assembling the stator-windings, the main-field coils 5' are first put in place, and then the coils of the interpole-winding 6 are slipped over the parallel-sided interpoles 13. In order to get the main-field coils 5' into place, the coil-sides must be spread temporarily, for the purpose of passing over the main-pole tips 14', as shown in Fig. 2. To assist in getting the coil-sides over the pole-tips, we prefer to use suitable spreaders or guiding-forms 24, to act like "shoe-horns," as shown in Fig. 2. The pre-formed coil 5' may initially, as shown, have the form which it is finally to have, in its final position on the shank-portion of a main-field pole 14, as shown in dotted lines at 25 in Fig. 2. As the coil is pushed down into place, the guide or spreader 24 spreads the coil-sides apart, so that they pass over the pole-tips 14' and into the "back" portions 15 of the slots, as shown in dotted lines at 25 in Fig. 2, after which the coil-sides snap partially back, and can be pressed into final position, in the "front" portions 16 of the slots, in snug engagement with the pole-shank portions of the main poles 14, as shown in pull lines in Fig. 2. The temporary guide or spreader 24 may then be removed.

The spreading apart of the coil-sides of our coil is accomplished with relative ease, due to the fact that the individual strands 20 of copper in each end-portion 23 of the coil may retain their original overall length during the spreading and retracting of the coil-sides. Thus, there is no stretching or buckling of any strand. This mathematical relation is shown by Fig. 3, from which it is clear that the initial (and final) length of the outer strand AED of the end-winding 23 is $\pi(R_1 + W)$, while the length of the same strand when the coil is ex-

panded is A'E'D' or $\pi(R_2 + W) + S$, and these two lengths will be equal if $\pi(R_1 - R_2) = S$. Similarly, the initial (and final) length of the inner strand BFC of the end-winding 23 is πR_1 , while the length of the same strand when the coil is expanded is B'F'C' or $\pi R_2 + S$, so that these two lengths will also be equal under the same condition, namely when $\pi(R_1 - R_2) = S$. Therefore, there is no stretching or buckling of any strand of the end-turns 23 when the coil is expanded or retracted.

However, the strands 20 of the end-turns 23 must slide along one another a small amount when the coil is expanded or retracted, and hence, in order to retain flexibility, the end-portions 23 of the pre-formed main-field coil 5' must not be varnish-impregnated with an adherent varnish until the coil has been passed over the pole-tips 14' into the stator-slots 12. Varnish-treatment after the winding-operations are complete is considered adequate for these end-portions 23.

Main-field coils, made in accordance with the principle just described, may have either many turns per coil, or only a few turns per coil, as conditions may require. When many turns are required, say from 15 to perhaps 40 turns per coil, as in alternating-current railway-motor practice, each turn may be composed either of a single small conductor or strand, or of a few strands in parallel, and all of the coils 5' of the main-field winding 5 would be commonly connected in multiple. In a motor having only a few turns per coil, each turn would be composed of several strands in multiple, and the coils would be connected either all in series or possibly in two or three multiple paths.

In either of these two types of coils, the amount of stranding, in both the radial and lateral (or circumferential) directions, must be sufficient to give the required degree of flexibility.

The foregoing and other changes may be made in the coil-design, without departing from the essential spirit of our invention. We desire, therefore, that the appended claims shall be accorded the broadest scope of interpretation which is consistent with their language.

We claim as our invention:

1. An electric machine having a relatively stationary member and a relatively movable member separated by a gap, one of said members being characterized by having a slotted magnetizable core, said slots defining parallel-sided interpoles interspersed between main-field poles having shank-portions and pole-tips, a main-field winding having preformed coils fitting over said pole-tips and onto the shank-portions of the main-field poles, and an interpole-winding having coils disposed on said interpoles and holding the side-portions of said main-field coils in place on the main-field shank-portions.

2. The invention as defined in claim 1, characterized by each of said main-field coils being composed of a plurality of thin, flexible conductors, having straight coil-sides which are completely insulated and hardened, and having flexible end-turn portions in which, in the preformed condition of the coil, it is possible for the different strands to have a small amount of end-wise slippage over each other as the preformed coils are expanded or retracted in the process of passing the coil over the pole-tips.

3. A series commutator dynamo-electric machine having a relatively stationary field-member and a relatively rotatable armature-member

having a commutator associated therewith and being separated from said field-member by an airgap, said field-member having more than two poles and comprising a stack of magnetizable punchings having a plurality of slots on their airgap-periphery, said slots defining parallel-sided interpoles interspersed between main-field poles having shank-portions and pole-tips, a main-field winding having preformed coils fitting over said pole-tips and onto the shank-portions of the main-field poles, and an interpole-winding having coils disposed on said interpoles and holding the side-portions of said main-field coils in place on the main-field shank-portions.

4. The invention as defined in claim 3, characterized by each of said main-field coils being composed of a plurality of thin, flexible conductors, having straight coil-sides which are completely insulated and hardened, and having

10

5

flexible end-turn portions in which, in the pre-formed condition of the coil, it is possible for the different strands to have a small amount of end-wise slippage over each other as the preformed coil is expanded or retracted in the process of passing the coil over the pole-tips.
